Thomas B. Kelly

UNITED STATES PATENT OFFICE.

WILLIAM LLOYD GILCHRIST, OF ALBANY, OREGON.

AUTOMATIC HYDRAULIC BALL COCK.

Application filed June 2, 1925. Serial No. 34,398.

My invention relates to ball cocks for use in toilet flushing tanks, cisterns, overflows and in any and all places where it is desired to control the filled level of the liquid to be removed therefrom through the siphonic principle or through valved control mechanism.

My invention consists of new, novel and useful means for accomplishing this result by automatic hydraulic means.

My device consists primarily of a valve adapted to being quickly opened, and when closed to have cushioning means provided for the prevention of a water hammer.

A further object of my invention consisting in a cam actuator, adapted to having imparted thereto, two speeds of opening, one to crack the valve, or to break the initial set of the valve, and after this has been accomplished, a quick opening of the same through the cam pawl engaging a sloping surface on its opposite end adapted to increase the speed of opening thereof.

A further object of my invention consists in the quick release of the cam actuator.

A further object of my invention consists in providing a splash skirt around the outer periphery of the valve cock body to confine the liquids escaping therefrom, and thereby preventing a splashing of the escaping liquids.

With these and incidental objects in view, the invention consists in certain novel features of construction and combination of parts, the essential elements of which are set forth in the appended claims and to a preferred form of embodiment of which is hereinafter shown with reference to the drawings which accompany and form a part of this specification.

In the drawings,—

Fig. 1 is a side elevation, partially in section, of my assembled device, illustrating the relation of the different parts and in position, within the valve cock.

Fig. 2 is a front elevation, taken on line 2—2 of Fig. 1, looking in the direction indicated.

Fig. 3 is a side elevation of the valve cock body with the automatic mechanism removed therefrom.

Fig. 4 is a side elevation of the valve stem, shown removed from the valve cock.

Fig. 5 is a side elevation of the automatic escapement unit, shown detached from the valve cock, illustrating the escapement, the cam actuator, and the ball carrying arm as a unit assembly.

Fig. 6 is a rear view looking in the direction indicated by the arrows in Fig. 5.

Like reference characters refer to like parts throughout the several views.

1 is the body of the valve cock having a longitudinal cylindrical opening 2 therethrough, adapted to the passage of the valve stem 3 therethrough, the side walls of the valve cock body forming suitable bearing for maintaining the same in alignment and in position. A tapered inner wall 4, is disposed on the inner surface of the valve cock body, its sloping surface terminating at the longitudinal cylindrical opening therethrough, forming the guideway for the valve stem. The valve stem 3 has a collar 5, adapted to engage with the tapering side walls of the valve body, so that as the valve is seating upon the seat 10 of the valve body, a quantity of the liquid will be trapped within the enclosure 7, and will escape about and past the collar 5, to lessen the water hammer that would be otherwise created by the instantaneous closing of the liquid passage through the valve. A valve face 8, of suitable valve material, as rubber, is disposed about the valve head 9, disposed on the lower end of the valve stem. The valve face 8 is adapted to engage with the seat 10. To maintain the valve stem in approximate position and to prevent its dropping from the body of the valve cock during assembly, or placement of the valve, I have provided a maintaining screw 11, for maintaining the valve stem in approximate position. The body of the valve cock is threaded at 12, for attachment to an inlet liquid conduit. The liquid as released from the conduit has a tendency, due to the in-rushing velocity, to normally maintain the valve in closed position. To actuate the same, a lever arm 13, is journaled about the pin 14. The ball rod 15, is attached to the lever arm 13. The float ball 16, is at-

tached to the ball rod 15. The lever arm 13, is journaled about the pin 14, but is not attached thereto in rigid relationship, having a pivotal relationship therewith, but the 5 actuator escapement 17, and the cam actuator 18 are secured in fixed relationship with the pin 14, and as the same is rotated about the rotating axis of the pin, the pin is rotated also. The full line position of the ball rod 10 and the escapement as shown in Fig. 1, illustrates the valve in a partially opened position.

The following movement occurs when the valve is opened; when the float 16 15 lowers and the actuator escapement 17 is turned in its pivotal bearing the lower surface of the cam actuator will engage the end of the valve stem and partially open the valve and that afterwards the 20 upper face 20 of the cam actuator will contact with the sloping surface 21 of the body portion and quickly move the valve into its full open position. In the full open position the actuator escapement will occupy the dotted line position 25 shown in Fig. 1. When the valve is closed by the pressure within the liquid supplying pipe the valve stem is raised to maximum height, and as the same is raised the cam 30 18 and the pin 14, journaled within the elongated slot 22, is raised to the top of the elongated opening in which position it remains until the cam contacts with the sloping surface at which time the pin 14 is carried to the bottom of the elongated opening. In this position the cam contacts with the stop shoulder 26 and the same is locked by the upper end of the cam engaging with the horizontal ledge 25, until the liquid 35 40 has escaped from the container to be emptied, the outflowing of the liquid is usually much more rapid than the inflowing and therefore the container will be quickly emptied. To prevent the splashing of the liquids entering through the valves, the same escapes through openings 27, of the body of the valve cock and to prevent the same from splashing or otherwise escaping from the container, I have provided a circumferential skirt portion 23, so that the incoming liquid is deflected downward by the skirt portion. After the container has been emptied usually by the siphonic principle, the ball 16 is raised by the incoming 45 50 liquid and in rising, the arm 13, engages with the surface 24 of the escapement actuator and in raising the same, the cam is disengaged from the ledge surface 25, of the valve cock body and the pressure on the valve stem closes the valve and in doing so returns the actuator mechanism to its normally closed and inoperative position, and the pin 14 is carried to the top of the elongated bearing. In the event that the pressure 55 60 65 should cease and the liquid be drained

from liquid conduit attached to the valve body the tank would drain through the valve.

One of the things accomplished by a device of this kind is the elimination of 70 the customary noises that generally prevail. In my invention I have produced a device that is silent and efficient in its operation. One of few parts and one that will not easily get out of order. 75

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow. 80

What I claim is,— 85

1. An automatic hydraulic ball cock, comprising a skirted valve body, a valve stem fitted longitudinally of the valve body and in slidable relation therewith, a valve head fitted to the valve stem, a valve seat within the valve body, a pin journaled in the valve body and above and in alignment with the valve stem; a cam actuator and an actuator escapement in fixed relation with the pin, and a lever arm journaled about the pin and adapted to actuate the actuator escapement, the cam actuator and the valve stem; a float ball and a ball rod for actuating the lever; and means for preventing a water hammer upon the seating of the valve, comprising a tapered inner side wall in the valve body and a collar on the valve stem adapted to be brought into a position adjacent said tapered wall when the valve is closed. 90 95 100 105

2. An automatic hydraulic ball cock, comprising a skirted valve body having escapement openings therefrom, and adapted for threaded engagement with a liquid carrying conduit, a valve stem fitted longitudinally of the valve body and in slidable relation therewith, a collar and valve head on the valve stem, actuating means adapted for a float ball for seating and opening the valve and means for preventing a water hammer when the valve is seated comprising a liquid trap within the valve body and about the valve stem wherein liquid is trapped therein by the collar about the valve stem partially closing the trap as the valve stem is raised during the seating of the valve. 110 115 120 125

3. An automatic hydraulic ball cock, comprising a threaded skirted, valve body, a valve stem disposed central of the valve body 125 and adapted for slidable relationship therein, an elongated bearing slot disposed in the upper end of the valve body, a pin journaled within the elongated bearing slot, a cam actuator and an actuator escapement carried 130

in fixed relation with the pin, a lever arm journaled about the pin having a ball rod and a float ball disposed in threaded relation therewith, said cam actuator engaging 5 with the upper end of the valve stem, a sloping body portion of the cock body contacting with the cam actuator, when said pin, cam

actuator and actuator escapement are rotated, and forcing said pin, cam actuator, escapement actuator and valve stem downward; and means to prevent a water hammer upon the reseating of the valve. 10
